UNITED STATES PATENT OFFICE.

HENRY FLAD, OF ST. LOUIS, MISSOURI.

ELECTRICAL CONNECTOR IN PIPE-COUPINGS FOR AIR-BRAKES.

SPECIFICATION forming part of Letters Patent No. 296,547, dated April 8, 1884.

Application filed June 7, 1883. (No model.)

To all whom it may concern:

Be it known that I, HENRY FLAD, of St. Louis, in the county of St. Louis and State of Missouri, have invented certain new and useful Improvements in Electrical Connectors in Pipe-Couplings for Air-Brakes; and I do hereby declare the following to be a full, clear, and exact description of the invention, such as will enable others skilled in the art to which it appertains to make and use the same.

My invention relates to a combined coupling for hose or pipes, and electrical conductors arranged therein.

On the same date with this application I have filed two applications for patents for improvements in electric air-brakes for railway-cars; and the main object of my present invention is to provide means whereby the electrical conductors which are arranged in the air-pipes on the cars may be automatically connected and disconnected between cars simultaneously with the coupling and uncoupling of the air-pipes or connecting-hose. It will be obvious, however, that the invention may be used for coupling pipes or hose and inclosed electrical conductors used for any purpose.

The invention consists in certain novel combinations of devices for accomplishing the object above stated, and will be readily understood from the following particular description, in connection with the accompanying drawings, in which—

Figure 1 is a longitudinal central section of an air-hose coupling provided with electrical connecting devices according to my invention, the hose-coupling being such as used in the Mallinckrodt system of air-brakes. Fig. 2 is a detached side view, and Fig. 3 an end view, of the insulating-casing for the spring-controlled connecting-rod. Fig. 4 is an outer end view of one of the coupling-clutches. Fig. 5 is a section of the same on line $x-x$ of Fig. 4. Fig. 6 is a section on line $x'-x'$. Fig. 7 is a section on line x^2-x^2 . Fig. 8 is a longitudinal central section of a Westinghouse hose-coupling provided with devices for connecting electrical conductors according to my invention. Fig. 9 is a similar section of another form of West-

inghouse coupling provided with my improvement. Fig. 10 is a detached side view of one of the insulating-casings. Fig. 11 is a longitudinal central section of a coupling commonly used in vacuum-air-brake systems, the same being provided with my improvement.

Referring to Fig. 1, A A are the metallic thimbles of the members of the coupling, which are secured to the hose B B in the usual manner. C C are the coupling-clutches screwed onto the thimbles, and D D are annular vulcanized-india-rubber gaskets filled within the clutches, and having outwardly-projecting flanges, which are clamped between the inner shoulders of the clutches and the ends of the thimbles. When the clutches are engaged, the edges of these gaskets come together and form an air-tight joint.

In each of the thimbles A is fitted a tubular casing, E, formed of some non-conductor of electricity, preferably hard rubber or gutta-percha, said casing being formed of two semi-cylindrical parts, e and e', as shown in Figs. 2 and 3, having heads in which are openings o o o o.

In each head of the casing is formed a central opening, p, half of the said opening being in each part of the head.

Centrally in the casing, and projecting at each end through the openings p p, is arranged a metallic rod, F, as shown in Fig. 1, said rod having at its outer projecting end a flat metallic head, f, and being provided at an intermediate portion of its length, within the casing, with a shoulder, f', against which bears one end of a spiral spring, f², surrounding the rod and having its inner end bearing against the inner head of the casing. The tension of the spring f² is such that it tends to force the rod outward, the outward movement of the rod being such that its head will stand out beyond the rubber gasket, this movement being limited by the shoulder f', which comes against the head of the casing.

In placing the rod F in position the two parts of the casing E are separated. The rod is placed in the notches in the parts of the heads of one portion of the casing, with the spring f² and the shoulder f' in proper position, and

then the other semi-cylindrical portion is applied to complete the casing, which is inserted in the thimble A and secured by screws *s s.*

To the inner end of each rod F is to be electrically connected, by soldering or otherwise, the end of an insulated conducting-wire, W, which, it will be understood, leads through the hose and air-pipes of a railway-car when my invention is applied for coupling the pipe and conductors of an electric air-brake system; or the wires may be led through sections of pipe or hose of any length for other purposes.

It will be obvious that when the two clutches of the hose-coupling are coupled together the heads of two opposite rods, F F, will be automatically brought into contact with each other, and the rods will both be forced slightly inward, the two springs acting to press the heads together and maintain a good though flexible electrical contact.

I do not limit myself to any particular form of hose or pipe couplings; but I find that shown in Fig. 1 to be very efficient. In this coupling the two clutches C are precisely similar in construction, each having radially-projecting segmental flanges b b diametrically opposite each other, and segmental hooks b' b' adjacent to the flanges and projecting forward beyond them. Between the flanges and hooks on one side are spaces, as at b², through which the hooks of an opposite clutch may be passed, and when two clutches are thus brought together and turned in opposite directions the hooks of one may be engaged behind the flanges of the other, and an efficient coupling effected.

In regard to the form of hose-coupling shown in Fig. 8, it is only necessary to say that it is a form in common use, the two members of the coupling being dissimilar. The insulating-casings E and E' are each formed of two semi-cylindrical portions, substantially as shown in Fig. 2, and are fitted into the two thimbles A and A² and the chambers in front thereof. The spring-rod F' in the casing E' projects outward a considerable distance into the chamber of the coupling member K, and is adapted to enter the chamber of the coupling member K' when the latter is inserted in the former, as shown, so that its head may come in contact with the head of rod F', which does not project so far beyond its casing.

The construction and operation of the electrical connecting-rods is similar to that of the rods shown in Fig. 1, except that they project different distances beyond their casings. Both the rods, even when at their outer limit of movement, have their heads well within the chambers of the coupling members, and are therefore not liable to accidental injury when the members are uncoupled.

The hose-coupling shown in Fig. 9 is also in common use without the electrical connecting devices. This coupling has similarly-constructed opposite members, K² and K³, which lap and interlock with each other, bringing

the inner open ends of the cup-like portions L L opposite each other, the axes of the cups being at right angles to the axes of the thimbles A³ A³. These cup-like portions are in communication through lateral openings with the thimbles, and have rubber gaskets d d at their open ends to fit together and form an air-tight joint. Within said cup-like portions are fitted the insulating-casings E³ E³, having lateral openings e' to the thimbles. At their outer ends they are provided with sockets e⁴, and at their inner ends have partial heads or cross-bars e⁵, with central passages. Through these central passages are arranged the short metallic rods F³, having their outer projecting ends provided with contact-heads f³, and their inner ends inserted in the sockets e⁴. Inside of the casings the rods have shoulders f⁴, to which are connected the conducting-wires W, and against the shoulders bear the springs f⁵, to force the heads into contact with each other.

The insulating-casings, as shown in Fig. 10, are each composed of two semi-cylindrical parts, which may be taken apart to prevent the insertion of the rod and spring substantially in the same manner as the casings in Fig. 1.

In the vacuum-brake hose-coupling shown in Fig. 11 each of the curved metallic springs F⁶ is secured intermediately to one side of the thimble A⁴, but is insulated therefrom. The inner end of the spring is electrically connected with the conducting-wire W, and its outer end is provided with a metal contact-head, f⁵, which the spring is bent and adjusted to hold normally a little outside of the gasket D, so that when the two members of the coupling are coupled together the heads of the two springs will come in elastic contact with each other, and their tension will maintain a good electrical connection.

Having fully described my invention and explained the application of the same under various conditions, I claim—

1. The combination, with the sections of a pipe-coupling and insulating-casings located within the coupling-sections, said casings provided with skeleton end bearings, of spring-actuated metallic contacts supported in the bearings of the insulated casings, and electrical conductors connected with said contacts, substantially as set forth.

2. The combination, with the sections of a pipe-coupling and insulating-casings, each made in longitudinal sections, and provided with two-part end bearings, of spring-actuated metallic contacts supported in the bearings of the insulated casings, and electrical conductors connected with said contacts, substantially as set forth.

3. The combination, with the pipe-coupling sections and gaskets D D, secured thereto, of the insulated casings E, metallic contacts E f, spring f², and electrical conductors W, substantially as set forth.

4. The combination, with two sections of a pipe or hose coupling and gaskets of insulating material attached to each section to form an air-tight joint, of insulated casing located
5 within the coupling sections, and spring-actuated metallic contacts supported in bearings of the insulated casing, and electrical conductors connected with said contacts, substantially as set forth.

In testimony whereof I have signed this specification in the presence of two subscribing witnesses.

HENRY FLAD.
